ENGINE

André J. Meyer, Lexington, Ky., assignor to
 Mawen Motor Corporation, New York, N. Y., a
 corporation of Delaware

Application October 22, 1938, Serial No. 236,512

13 Claims. (Cl. 123—44)

- The present invention relates to internal combustion engines and has particular reference to radial engines of the kind in which a bank of radially arranged cylinders is encircled by an annular ported valve member between which and the cylinder bank there is relative rotary motion when the engine is in operation. In engines of this kind, the cylinder bank and the valve member may both rotate, but at different speeds, around a stationary crankshaft, or the crankshaft and cylinder bank may both rotate, in the same or opposite directions, with respect to a stationary valve member. In so far as the present invention is concerned, any specific relative rotational movement may be employed and for convenience the term bi-rotary will be employed herein to designate generically the various specific kinds of the type of engine under consideration and to which the invention relates.
- It is characteristic of engines of the bi-rotary type that the outer ends of the cylinders are open to provide cylinder ports which come into communication successively with the valve ports, and further that the cylinder bank carries with it sealing means moving in sliding contact with the inner face of the annular valve member for sealing the cylinder ports and also for sealing the valve ports during the times when they are not in registry with the cylinder ports.
- In engines of the bi-rotary type, in which ignition is effected by extraneous ignition means such as high tension spark plugs, glow plugs, or the like, such means are advantageously mounted in the valve member rather than in the engine cylinders, since when they are mounted in the valve member they are exposed to the heat and pressure of the combustion gases only for the comparatively very short time in the engine cycle which it takes for the cylinder ports to pass them, and not during the entire working and exhaust periods of the cycle as would be the case if they were mounted in the cylinders.

When such ignition devices are mounted in the valve member, they must, however, be mounted in recesses or pockets in order not to project from the inner face of the valve member, since such projection would interfere with the relative rotary movement between the valve member and the sealing parts in sliding contact therewith on the other hand. Each of the pockets or recesses is passed successively by the several cylinder ports, and at the instant when they are passed, ignition takes place. The resulting combustion fills the pocket with combustion gases under high pressure and before the piston of the cylinder in

which combustion has been effected can move downwardly to a sufficient degree to materially reduce the pressure of the combustion gases in the cylinder and in the ignition pocket which forms a part of the combustion space at the time of ignition, the cylinder port moves out of communication with the pocket, which is sealed until the next cylinder port comes into communication with it.

Consequently, the next cylinder to come into communication with the pocket, which cylinder contains a compressed charge intended to be fired by the ignition device in the pocket, is brought into communication with a certain quantity of spent combustion gases in the pocket which may still be under considerably higher pressure than the compression pressure within the cylinder, particularly if the seal between the valve member and the sliding sealing means is highly effective.

This charge of compressed spent combustion gas in the pocket has an adverse effect on the character of combustion obtainable in the succeeding cylinder. In the first place, the spent combustion gases envelop the ignition device and in the very short interval when the pocket is in communication with the engine cylinder, the turbulence created by the communication between the two chambers may be insufficient to permit fresh combustible gas from the cylinder to get to the vicinity of the point of ignition. If this occurs, the cylinder will fail to fire. Even if fresh combustion gases do get to the ignition device so that ignition occurs, the charge of fresh gas in the cylinder is diluted with the spent combustion gases from the pocket, which as previously noted may be at substantially higher pressure than that of the cylinder gases at the instant the cylinder comes into communication with the pocket. Consequently, the extent of dilution of the cylinder gases by spent gases from the pocket may be materially greater than would be indicated by the relation of the volume of the compression space in the cylinder at the instant of ignition to the volume of the pocket.

It is the general object of the present invention to eliminate the difficulties of the above described nature encountered in the operation of engines of the kind under consideration as heretofore constructed.

In accordance with the invention, this general object is accomplished by the provision of means whereby each of the pockets in which the ignition devices are located and which for convenience may be termed ignition pockets is intermittently

vented to a zone of low pressure between the times when it is in communication with the ports of successive cylinders.

The manner in which such venting is effected 5 in order to attain the above stated general object and other and more detailed objects of the invention will best be understood from a consideration of the ensuing portion of this specification taken in conjunction with the accompanying 10 drawings, illustrating the application of the principles of the invention to engine structures.

In the drawings:

Fig. 1 is a longitudinal section of a portion of a bi-rotary engine embodying the invention;

15 Fig. 2 is an elevation, partly in section, of the engine shown in Fig. 1 and looking from the right of Fig. 1;

Fig. 3 is a plan view of a part of the structure shown in Fig. 1;

20 Fig. 4 is a section taken on the line 4—4 of Fig. 3;

Fig. 5 is a section taken on the lines 5—5 of Figs. 3 and 4 and shows parts of additional cooperating elements;

25 Fig. 6 is a section taken on the line 6—6 of Fig. 5;

Fig. 7 is a view similar to Fig. 4 showing a different embodiment; and

30 Figs. 8, 9, and 10 are all views similar to Fig. 5 showing different embodiments.

35 Referring now to the drawings, the engine illustrated is of the kind in which the housing structure including the valve member is stationary and the cylinder bank and crankshaft revolve in opposite directions and at different speeds. The housing structure, which in this case is the mounting structure, comprises a forward member 10 and a rear member 12 between which the annular valve member 14 is fixed. The valve member is provided with a series of suitably spaced apart exhaust passages 16 and inlet passages 18 which at their inner ends terminate in ports in the inner sealing surface 20 of the valve member. This surface is preferably spherically curved. In the embodiment illustrated the cylinder bank comprises a crank case structure 22 carrying a plurality of radially arranged cylinders 24, each having a piston 26.

40 The crankshaft 28 provides a crank pin 30 to which the several pistons are connected in any suitable manner. In the embodiment illustrated this is accomplished through the medium of a master connecting rod 32 connected to one of the pistons and a series of link rods 34 which serve to connect the remaining pistons with the master 45 rod adjacent to the crank pin.

45 The desired relative speeds of rotation of the cylinder bank and the crankshaft and the timing of these two components with respect to the ported valve member is obtained by gearing 50 which in the illustrated embodiment comprises a crankshaft gear 36 meshing with a gear 38 fixed on shaft 40 which constitutes the power take-off shaft of the engine. Shaft 40 is mounted in the stationary mounting member 10 and has 55 fixed thereto a second gear 42 meshing with an idler gear 44 also mounted in the stationary structure and behind the plane of Fig. 1 of the drawings. The idler 44 meshes with gear 46 fixed to the rotatably mounted crank case structure.

60 As will be evident from Fig. 1, the crankshaft and the cylinder bank will be caused to rotate in opposite directions by the gears just described and their speeds of rotation will be determined by the gear ratios of the two trains of gears. Insofar as the present invention is concerned, any

suitable gearing arrangement between the component parts may be employed.

Each of the cylinders 24 is open at its outer end and the open ends of the cylinders are sealed by parts of the sealing means carried by the cylinder bank. These parts advantageously consist of annular sealing elements 48 in the form of cylindrical cuff-like members having spherically curved outer surfaces in sliding contact with the inner surface of the valve member, and barrel portions telescopically engaging the walls of the open outer ends of the cylinders.

From Fig. 2 it will be evident that relative rotary movement between the cylinder bank and the valve member will bring the cylinder ports into and out of communication with the inlet and exhaust ports in the valve member. In order to seal the latter ports when they are not in communication with any cylinder port, a further portion of the sealing means carried by the cylinder bank is employed. This latter portion comprises an annular sealing member 50, the outer face of which is curved to mate with the curved inner surface of the valve member, with which it is in sliding contact. The sealing member is provided with a series of properly spaced apertures 52 which permit the sealing elements to extend through the sealing member into sliding contact with the valve member.

30 The valve member is provided with a series of ignition pockets 54 communicating with the inner side of the valve member, which pockets are located at suitably spaced intervals peripherally of the valve member so as to come into communication with the cylinder ports at the proper time for ignition in the particular engine cycle employed. In the embodiment illustrated, the engine is of the four stroke cycle type, having seven cylinders per bank. With this engine and with the cylinder bank and crankshaft rotating in opposite directions, each cylinder fires four times per revolution of the cylinder bank and at least four ignition pockets are required. In the embodiment illustrated these pockets are formed by the inner portions of suitably threaded bores extending through the valve member and into which spark plugs 56 are threaded. If the inner ends of the plugs are set substantially flush with the inner surface of the valve member, gas accumulating pockets will still be formed by the internal cavities of the inner ends of the plugs. Obviously, other kinds of ignition means resulting in the formation of other forms of ignition pockets may be utilized.

35 The sealing means is provided at spaced intervals with vent passages extending therethrough, these vent passages advantageously being located in the annular sealing member 50 and there being advantageously at least one such passage between each two adjacent cylinders of the bank. These passages are provided with inlets located to be brought into and out of communication with the ignition pockets by the relative rotary movement between the cylinder bank and the valve member, and the outlet ends of these passages are located so that they will serve to vent the ignition pockets to a zone of low pressure.

40 In the embodiment shown in Figs. 3 to 5, the vent passages 58, one of which is shown in these figures, are formed with inlet 60 at the outer surface of the sealing ring, located to register with the ignition pockets 54, which inlets communicate with a transverse passage extending through the sealing member to provide outlet

62 and 64 at the sides of the ring. These outlets advantageously communicate intermittently with the annular channels 66 and 68 formed respectively in the housing members 10 and 12. These 5 channels serve as drainage channels for excess lubricant discharged from between the sliding contact surfaces of the valve member and the sealing ring. These channels are not under material pressure and by venting the ignition pockets to these channels, any lubricant entering the inlets of the vent passages from the lubricated sliding surface will be carried back into the lubrication system.

As previously noted, the vent passages communicate only intermittently with these drain passages and in most instances the vent passages are advantageously opened only intermittently to any low pressure zone. Preferably they are opened only when their inlet ends are in communication with the ignition pockets. It will be apparent that if the ignition pockets and the valve ports are to communicate with the cylinder ports upon relative rotary movement between the engine parts, the ignition pockets must lie 20 in the same plane normal to the axis of relative rotation as the valve ports. From this it follows that if the inlet ends of the vent passages are to communicate with the ignition pockets they must necessarily, in other positions of rotation of the 25 parts, communicate with the valve ports. Consequently, if the vent passages were permitted to remain open at all times, communication between the valve ports and a low pressure zone would occur when the vent passages passed the valve 30 ports.

Intermittent communication between the valve ports and a low pressure zone, through the vent passages, would be undesirable in many cases, particularly in the case of supercharged engines, 40 since in such case substantial quantities of fresh gas might be lost through the vent passages because of the positive pressure in the intake manifold. Also, in the event pressure in the exhaust manifold were for any reason relatively high, appreciable quantities of exhaust gas might be 45 blown through the vent passages when the inlets passed the exhaust ports.

For the above reasons valve means are advantageously employed to close the vent passages, 50 particularly at times when the inlets thereof are in communication with the valve ports. Such valve means is advantageously arranged in the form of what may be termed a slide valve formed between the relatively rotating sealing member and the housing structure at the side of the sealing member.

In the embodiment illustrated in Fig. 5 the parts 10 and 12 in which the channels 66 and 68 are formed provide radially extending flanges 70 and 72 respectively which are in sliding contact with the side faces of the sealing ring 50. These flanges are advantageously continuous but may be circumferentially interrupted. In the embodiment illustrated they are continuous and are provided with ports peripherally spaced at suitable intervals and located to be passed by the outlets of the vent passages when the inlets of the passages are in communication with the ignition 70 pockets. One of such ports is indicated at 74 in Fig. 6. Obviously, many other specific forms of notched or otherwise interrupted slide valve structures may be employed for accomplishing the desired object of closing the vent passages 75 in desired positions of rotation thereof while per-

mitting them to function when they are in communication with the ignition pockets.

In the embodiment just described the sealing member 50 has been shown as of continuous one-piece construction. This sealing member may in some instances be of built-up construction consisting of a plurality of segmental shoes 76 (see Fig. 7) having openings 52 therein for the reception of the cylinder sealing elements and intermediate connecting or bridge shoes 78. In so far as the present invention is concerned, it is immaterial whether or not the sealing member is of one-piece or built-up construction and it will be evident from Fig. 7 that the shoes 76 may be provided with vent passages 58a which will function in the same manner as that previously described.

From the standpoint of manufacturing convenience and expense, it will be evident that vent passages extending radially straight through the sealing means are more advantageous than the laterally extending passages of the form shown in Fig. 5, and for aspirated engines, such passages may in some instances be used. An arrangement of this sort is shown in Fig. 8 in which the sealing member 50 is provided with a plurality of passages 58c extending radially directly through the member. These passages operate to vent the ignition pockets directly to atmosphere and if left open will provide communication between the inlet and exhaust ports and atmosphere as they pass the valve ports. In the case of an aspirated engine, communication of the passages 58c with the inlet ports would cause fresh air to be admitted to the manifold which in some instances might cause undesirable disturbance to the fuel air ratio of the fresh gas mixture. This may be avoided in very simple manner by the provision of a light spring valve 80 of the feather type, fixed to the sealing member by any suitable means such as the screw 82 and normally closing the outlet of the vent passage 58c. It will be evident that a light feather valve of this type will prevent flow of air through the vent passage to an inlet port, while at the same time the pressure required to cause the valve to open will be practically negligible so that when the vent passage passes an ignition pocket it will operate to vent the latter of the gases under pressure trapped therein. It will be apparent that for this type of vent passage any suitable form of check valve opening away from the ignition pockets may be employed.

Still another arrangement is illustrated in Fig. 9 wherein the vent passages 58b are in the form of laterally extending grooves, in the outer face of the sealing member. These grooves may extend either to one or both sides of the sealing member and in the embodiment shown discharge through these passages is controlled by a slide valve of the kind illustrated in Figs. 5 and 6.

In all of the embodiments previously described the inlets of the vent passages have been arranged in the same plane as that of the ignition pockets and valve ports. An alternative arrangement is illustrated in Fig. 10. In this form of construction the ignition pocket includes a laterally extending passage 54a having a branch providing an opening 54b in the surface of the valve member which is located laterally to one side of the lateral extremities of the ports in the valve member, these extremities being indicated by the dotted port lines 18. The sealing member is provided with vent passages 58d which may as in the embodiment illustrated open laterally

of the sealing member, or pass directly therethrough.

- In this form, it will be evident that the vent passages 58d will never register with the valve ports and consequently these passages do not require to be closed against communication with these ports. This arrangement has, however, the disadvantage that, due to the fact that the ignition pockets are momentarily subjected to the working pressures in the cylinders when these pockets communicate with the cylinder ports at the moment of ignition, the sealing against loss of the gas under the working pressure in the cylinders must depend on the seal between the face of the valve member 14 and the sealing member 50. This latter member is intended primarily merely for the purpose of sealing the ports and is consequently not necessarily constructed to provide a seal against high gas pressure.
- For this reason the forms of construction in which the vent passages are arranged with their inlets in the same plane as the openings of the valve ports and ignition pockets are to be preferred.
- Many other specific modifications of the invention will suggest themselves to those skilled in the art and it is to be understood that the scope of the invention is not limited to the embodiments hereinbefore described by way of example but is to be considered as including all forms of construction falling within the scope of the appended claims.

What is claimed is:

1. In a bi-rotary engine, an annular ported valve member, sealing means mounted for relative rotary movement with respect to said valve member, ignition pockets opening inwardly of the valve member, and venting means carried by said sealing means for placing said pockets temporarily in communication with a zone of low pressure due to said relative rotary movement.
2. In a bi-rotary engine, an annular ported valve member, an annular sealing member mounted for relative rotary movement with respect to said valve member, ignition pockets opening inwardly of the valve member, a plurality of vent passages formed in said sealing member, each of said passages having an inlet located to pass said ignition pockets due to said relative rotary movement, and means for closing said passages in predetermined relative positions of the sealing member and the valve member.
3. In a bi-rotary engine, an annular ported valve member, sealing means mounted for relative rotary movement with respect to said valve member for intermittently closing said ports, ignition pockets opening inwardly of the valve member, a plurality of vent passages formed in said sealing means, each of said passages having an inlet located to pass said ignition pockets due to said relative rotary movement and an outlet, and means rotationally fixed with respect to said valve member for closing the outlets of said passages in predetermined relative positions of said sealing means and said valve member other than the relative positions thereof in which said inlets communicate with said ignition pockets.
4. In a bi-rotary engine, housing structure including an annular ported valve member, a cylinder bank mounted for relative rotary movement with respect to said valve member, sealing means carried by said cylinder bank in sliding contact with the valve member, a plurality of vent passages formed in said sealing means and a plurality of ignition pockets in said valve mem-

ber, each of said passages having an inlet located to pass said pockets due to said relative rotary movement and an outlet spaced laterally of the inlet, said housing structure including portions covering said outlets in predetermined relative position of the cylinder bank and the valve member other than the relative positions thereof in which said inlets communicate with said ignition pockets.

5. In a bi-rotary engine, an annular ported valve member, a cylinder bank mounted for relative rotary movement with respect to said valve member, sealing means carried by said cylinder bank in sliding contact with said valve member, a plurality of ignition pockets in said valve member, a plurality of vent passages constituting laterally extending grooves formed in the outer surface of said sealing means, each of said passages having an inlet located to pass said pockets due to said relative rotary movement and an outlet, and means for opening and closing the outlets of said passages in different predetermined relative positions of rotation of the sealing means and the valve member.

6. In a bi-rotary engine, housing structure including an annular ported valve member, an annular sealing member mounted for relative rotary movement with respect to said valve member, a plurality of ignition pockets in said valve member, a plurality of vent passages formed in said sealing member, each of said passages having an inlet located to pass said pockets due to said relative rotary movement, and an outlet located at the side of the sealing member, said housing structure including portions located to cover said outlets in predetermined relative positions of the sealing member and the valve member other than the relative positions thereof in which said inlets communicate with said ignition pockets.

7. In a bi-rotary engine, an annular ported valve member, an annular sealing member mounted for relative rotary movement with respect to said valve member, a plurality of ignition pockets in said valve member, a plurality of vent passages constituting laterally extending grooves formed in the outer surface of said sealing member, each of said passages having an inlet located to pass said pockets due to said relative rotary movement and an outlet, and means for closing the outlets of said passages in predetermined relative positions of the sealing member and the valve member other than the relative positions thereof in which said inlets communicate with said ignition pockets.

8. In a bi-rotary engine, housing structure including an annular ported valve member, an annular sealing member mounted for relative rotary movement with respect to said valve member, a plurality of ignition pockets in said valve member, a plurality of vent passages formed in said sealing member, each of said passages having an inlet located to pass said pockets due to said relative rotary movement and an outlet located at the side of the sealing member, said housing structure providing an annular channel adjacent to the side of said sealing member, and means located between said channel and the adjacent side of the sealing member, said means being located to close the outlets of said passages in predetermined positions of rotation of the sealing member with respect to the valve member and to permit communication between said outlets and said channel when the

inlets of said vent passages are in communication with said ignition pockets.

9. In a bi-rotary engine, a valve member having a plurality of peripherally spaced inlet ports and a plurality of peripherally spaced ignition pockets therein, sealing means mounted for relative rotary movement with respect to said valve member, a plurality of vent passages formed in said sealing means, said passages having inlets located to pass said ignition pockets and said ports due to said relative rotary movement, and automatic valve means operable to close said passages when said inlets are in communication with said valve ports and to open the passages when said inlets are in communication with said ignition pockets.

10. In a bi-rotary engine, a valve member having a plurality of peripherally spaced inlet ports and a plurality of peripherally spaced ignition pockets therein, sealing means mounted for relative rotary movement with respect to said valve member, a plurality of vent passages formed in said sealing means, said passages having inlets located to pass said ignition pockets and said ports due to said relative rotary movement, and means cooperating in sliding relation with said sealing means to close the outlets of said passages when the inlets thereof pass said inlet ports and to open the outlets of said passages when the inlets thereof pass said ignition pockets.

11. In a bi-rotary engine, an annular ported valve member having a plurality of ignition pockets therein, sealing means arranged for relative rotary movement with respect to the valve member, a plurality of vent passages formed in said sealing means, said passages having inlets located to pass said ignition pockets due to said relative rotary movement, and an automatically operable check valve for controlling each of said vent passages, said check valves being arranged to open away from the inlets of the passages.

12. In a bi-rotary engine, an annular ported valve member having a plurality of ignition pockets therein, an annular sealing member arranged for relative rotary movement with respect to the valve member, a plurality of vent passages extending in generally radial direction through said sealing member and having inlets located to pass said ignition pockets due to said relative rotary movement, and a spring valve located to cover the outlet of each of said passages, said spring valves being arranged to be opened by fluid under pressure admitted to said passages from said ignition pockets. 5

13. In a bi-rotary engine, an annular ported valve member having an inner sealing surface and a plurality of valve ports and a plurality of ignition pockets opening through said surface, said ports and pockets lying in a common plane, a cylinder bank mounted for relative rotary movement with respect to said valve member, said cylinder bank including a plurality of cylinders having ports at their outer ends lying in said plane, and an annular sealing member having an outer sealing surface cooperating in sliding relation with the sealing surface of the valve member to close said valve ports between times of communication thereof with the cylinder ports, passages formed in said valve member each communicating with an ignition pocket and having an outlet located in the sealing surface of the valve member laterally to one side of the lateral extremities of said valve ports, and a plurality of vent passages formed in said sealing member having inlets located in the sealing surface of the sealing member to pass the outlets of the first mentioned passages due to said relative rotary movement and to thereby vent said ignition pockets. 15 20 25 30 35 40
